DESIGN FOR A PEDESTAL.

No. 37,542.

Specification for Design.

Patented Sept. 12, 1905.

Application filed June 30, 1904. Serial No. 214,807. Term of patent 14 years.

To all whom it may concern:

Be it known that I, CHARLOTTE S. KOHLER, a citizen of the United States, residing in Sheboygan, in the county of Sheboygan and State of Wisconsin, have invented a new, original, and ornamental Design for Pedestals, of which the following is a specification, reference being had to the accompanying drawing, which forms a part of this specification.

The figure of the drawing is a perspective view of a pedestal, showing my new design.

I claim—

The ornamental design for a pedestal, as shown.

CHARLOTTE S. KOHLER.
